UNITED STATES PATENT OFFICE

158,557

PERFUME BOTTLE

Eric de Kolb, New York, N. Y., assignor to Gou-rielli, Inc., New York, N. Y., a corporation of
New York

Application January 24, 1949, Serial No. 414

Term of patent 7 years

(Cl. D58—9)

To all whom it may concern:

Be it known that I, Eric de Kolb, a citizen of the United States of America, residing at 470 Park Avenue, New York city, in the county of New York and State of New York, have invented a new, original, and ornamental Design for a Perfume Bottle, of which the following is a specification, reference being had to the accompanying drawing, forming part thereof.

In the drawing:

Fig. 1 is a front elevational view of a perfume bottle, showing my new design;

Fig. 2 is a rear elevational view of the same;

Fig. 3 is a side elevational view according to the present invention.

I claim:

The ornamental design for a perfume bottle, as shown.

ERIC DE KOLB.
